TOOL RETAINER FOR PERCUSSIVE TOOLS

Filed Jan. 8, 1948

UNITED STATES PATENT OFFICE

2,489,923

TOOL RETAINER FOR PERCUSSIVE TOOLS

Paul H. Nast, West Springfield, Mass., assignor to
Worthington Pump and Machinery Corpora-
tion, Harrison, N. J., a corporation of Delaware

Application January 8, 1948, Serial No. 1,157

3 Claims. (Cl. 279—19.1)

1

This invention relates to percussive tools and, in particular, refers to an improved retainer for drill steels, moil points, clay spades, chisels, etc.

An object of this invention is to simplify the construction and operation of tool retainers for drill steels, moil points, clay spades, chisels, etc.

Another object is to eliminate positive fastening means, such as nuts or cotter pins, which may be shaken loose from the retainer during operation of the percussive tool.

With these and other objects in view, as may appear from the accompanying specification, the invention consists of various features of construction and combination of parts, which will be first described in connection with the accompanying drawings, showing a tool retainer for percussive tools of a preferred form embodying the invention, and the features forming the invention will be specifically pointed out in the claims.

In the drawings:

Figure 1 is a longitudinal section through the chuck end of the cylinder of a percussive tool and shows the improved retainer in position to hold a drill steel in the cylinder.

Figure 2 is a side elevation, partly in section, taken from the right of Figure 1.

Figure 3 is a bottom view of the structure shown in Figure 1.

Figure 4 is a detail of the fulcrum pin.

Figure 5 is an end view of the pin shown in Figure 4.

Referring more particularly to the drawings, a moil point 1 is slidably mounted in a sleeve 2 carried by the cylinder 3 of the percussive tool (fragmentally shown). The moil point or other tool has the usual collar 4 which strikes the sleeve 2 to limit its insertion into the cylinder 3. The retainer mechanism 5 comprises a removable stop which is spaced from the sleeve 2 and adapted to engage the collar 4 to prevent the moil point or other tool 1 from falling out of the cylinder 3.

In order to support the retainer mechanism 5, the cylinder 3 is preferably provided with an elongated protuberance 10 which is generally disposed so as to be parallel to the cylinder 3 and the moil point 1. The protuberance 10 is bifurcated at its lower end to provide parallel legs 11 and 12. Its upper end has a bore 13 which, preferably, is slightly inclined inwardly toward the axis of the cylinder 3 and moil point 1.

The retainer latch 15 is pivotally mounted between the legs 11 and 12. This is accomplished by means of a novel fulcrum pin 17 which extends 55

2

through a cylindrical hole 16 in the latch 15 and rests in suitable holes 18 in the legs 11 and 12. The pin 17 has a flanged head 19 which has a flat 20 on one side. As shown in Figure 2, the pin 17 is inserted in the legs so that the flanged head 19 bears against the outside of the leg 11. This leg has a flat locking surface 21 on the outside which is slightly spaced from the flat 20 but which engages it to prevent rotation of the pin 17 and to provide it with a substantially fixed rotary position which it always assumes when removed and replaced.

The central portion of the pin 17 is turned down or decreased in diameter to provide shoulders 23 which are spaced apart by a distance equal to or greater than the thickness of the latch 15. These shoulders are disposed with relation to the flat 20 so that, when the pin is in locked rotary position with surface 21, they will at least be in that half 20 of the pin 17 which faces the bore 13. The groove 23' is preferably of the same diameter as the hole 16 and, hence, has its axis offset. In assembly, spring pressure, applied by means to be herein-after described, forces the latch 15 into the groove 23' between the shoulders 23 so that the edges of the hole 16 bear against these shoulders. It will be realized that when this occurs the pin 17 is locked in transverse position with respect to the latch pin 15 and legs 11 and 12. Thus, with respect to its own axis, the pin 17 cannot be rotated or moved axially when it is assembled with the latch 15 under spring pressure. This feature obviates the necessity for a nut or cotter pin to hold the pin 17 in place and thus makes it possible to provide a more streamlined appearance. The pin 17 may, of course, be easily removed by releasing spring pressure on latch 15 so that the latch may be withdrawn from groove 23' and the pin slipped out of holes 16 and 18.

The latch 15 has a stop face 25 at its inner end which, as shown in Figures 1 and 3, is adapted to engage and stop the collar 4 but permits movement of the moil point 1. The latch 15 is recurved so that its outer end has an inside face 26 which abuts the protuberance 10, when the latch is in closed position, to prevent further pivotal movement of the latch 15 in a direction which would swing the stop face 25 down and away from the moil point or other tool.

As already indicated, spring pressure acts on the latch 15 to hold it in closed position (full lines in Figure 1) and in the groove 23'. This pressure is provided by a lock pin 30 which is slidably mounted in the bore 13 and has a compression

spring 31 bearing upon it and upon the retainer cap 32 which is threaded into the top of the bore 13. When the pin 30 seats on a shallow flat 33 which is formed on the inner periphery of the latch 15, the latch 15 is yieldably held in closed position. It will be noted that because of the inward inclination of the bore 13 that the line of action of the pin 30 is between the moil point 1 and the axis of pin 17 thus tending to bias the latch 15 to the closed position. If desired, a removable bushing 35 may be provided for bore 13 to take the wear occasioned by sliding movement of the pin 30. Bushings 36 and washers 37 may also be provided to take the wear of the pin 17 and latch 15.

In order to open the latch 15, leverage is applied to the outer end 26 and the pin rides up out of the flat 33 against the force of spring 31 to permit pivotal movement of the latch 15 on pin 17 to dotted line position A. In this position the stop face 25 is adjacent the pin 30 as shown in Figure 1. The moil point 1 will then drop out of the cylinder 2.

What is claimed is.

1. In a tool retainer for a percussive tool the combination of a protuberance offset from the tool axis and having spaced longitudinal legs with coaxial holes therein, a retainer latch having a hole therein disposed between the legs, a pin mounted in the leg holes and extending through the latch hole, said pin having a groove of substantially the diameter of the latch hole in which the latch is seated, cooperating locking surfaces on the pin and a leg to prevent substantial rotation of the pin, and resilient means inclined toward the tool axis yieldably holding the latch in the groove.

2. In a tool retainer for a percussive tool the combination of an elongated protuberance offset from the total axis, a retainer latch having a hole therein, a pin mounted in the protuberance

and extending through the hole to pivotally connect the latch to the protuberance, said pin having a groove in which the latch is seated, said protuberance having a bore with its axis inclined toward the tool axis and intersecting the outer surface of the latch at a point between the tool axis and the axis of the pin, a locking pin slidably mounted in the bore, and resilient means yieldably forcing the locking pin against the outer surface of the latch to hold the latch in the groove.

3. In a tool retainer for a percussive tool the combination of an elongated protuberance offset from the tool axis and having spaced longitudinal legs with coaxial holes therein, a retainer latch having a hole therein disposed between the legs, a pin mounted in the leg holes and extending through the latch hole, said pin having a groove of substantially the diameter of the latch hole in which the latch is seated, cooperating locking surfaces on the pin and a leg to prevent substantial rotation of the pin, said protuberance having a bore with its axis inclined toward the tool axis and intersecting the outer surface of the latch at a point between the tool axis and the axis of the pin, a locking pin slidably mounted in the bore, and resilient means yieldably forcing the locking pin against the outer surface of the latch to hold the latch in the groove.
